UNITED STATES PATENT OFFICE.

HARVEY S. ANDERSON, OF GERMANTOWN, OHIO.

ADJUSTING DEVICE FOR CRUSHERS.

Application filed July 25, 1916. Serial No. 111,142.

To all whom it may concern:

Be it known that I, HARVEY S. ANDERSON, a citizen of the United States, residing at Germantown, in the county of Montgomery and State of Ohio, have invented certain new and useful Improvements in Adjusting Devices for Crushers, of which the following is a specification.

My invention relates to crushers for rocks, 10 ore, or other materials and more particularly to an adjusting or spacing device for crushers of the rotary disc type.

The object of the invention is to simplify the structure as well as the means and mode 15 of operation of the adjusting or spacing means for the crushers or other devices whereby they will not only be cheapened in construction, but will be more efficient in use, capable of being easily and quickly adjusted, 20 economical, positive and unlikely to get out of repair.

A further object of the invention is to provide improved means whereby any desired degree of adjustment may be secured.

With the above primary and other incidental objects in view, as will more fully appear in the specification, the invention consists of the features of construction, the parts and combinations thereof, and the mode of operation, or their equivalents, as 30 hereinafter described and set forth in the claims.

Referring to the drawings, Fig. 1 is a longitudinal sectional view of a portion of a disc crusher to which the invention forming the subject matter hereof has been applied. Two forms of embodiment of the invention are shown in Fig. 1. Fig. 2 is a longitudinal sectional view of the adjusting means or 35 spacer forming the subject matter hereof. Fig. 3 is a similar view of a modification of the spacer or adjusting device. Fig. 4 is a detail view of a modification of the spacer sleeve hereinafter referred to.

Like parts are indicated by similar characters of reference throughout the several views.

Referring to the drawings, 1 is the main rotary head of the crusher in which is loosely mounted the shaft 2 carrying the rotary head 3 and the crusher disc 4. Arranged in substantially parallel relation with the main rotary head 1 is a second head 5 adjustable in relation with the main head in which is 50 carried a second disc 6. The heads 1 and 5

rotate in unison independent of the shaft and head 3.

The main or primary crusher disc 4 is given a gyratory or wobbling movement whereby its periphery is caused to approach 60 and recede from that of the secondary disc 6. The material to be crushed is introduced between the discs 4 and 6 through the concentric orifice 7 and is carried by centrifugal tendency toward the peripheries of said 65 discs. The relative movement of the discs due to the wobble movement of the primary disc causes the material to be caught and crushed between the adjacent faces of the discs. The crushed material is discharged 70 by centrifugal tendency from the peripheries of said discs.

In practice there is considerable wear upon the discs which must be compensated for by the lateral adjustment of the head 5 75 toward the main head 1. As shown in Fig. 1 and also Fig. 2 the head 5 and main head 1 are connected one to the other by transverse bolts 8. It has heretofore been the practice to interpose a number of washers 80 or shims of various thicknesses which would be successively removed to permit the adjustment of the head 5. By the use of washers or shims only predetermined degrees of adjustment may be attained, dependent 85 upon the thickness of the shim or washer removed. Furthermore, inasmuch as a number of bolts 8 are located in spaced relation about the head 5, such procedure involves considerable amount of labor and 90 requires long periods of time to effect the necessary adjustment. To overcome the difficulty heretofore experienced there is provided intermediate the heads 5 and the main head 1 a sleeve 9 surrounding the bolt 95 8. This sleeve 9 preferably comprises a steel or iron core 9^a having a hardened exterior shell or surface 9^b preferably of manganese steel. Such a construction may be effected by first forming the core 9^a and 100 thereafter casting a manganese shell about the core. The sleeve 9 is counterbored and screw threaded to receive a screw threaded sleeve 10 also mounted upon the bolt 8 and engaging within the counter bore of the 105 sleeve 9. The screw threaded sleeve 10 is provided with a head 11 for the engagement of a wrench or spanner by which it may be turned upon the bolt 8 and within the screw threaded counter bore of the sleeve 9. A 110

locking nut 12 screw threaded upon the sleeve 10 serves to secure the parts in adjusted position.

The manganese or hardened sleeve 9 is of such extent as to project beyond the point of discharge of the discs 4 and 6 whereby the discharged material will strike the hardened surface of the sleeve which will not be materially affected thereby. As shown in Fig. 1, the adjusting portions of the spacer or adjusting member are offset in relation with the discharge point of the crusher where they cannot be injured by the discharged material. In the event that it is desired to adjust the crusher discs one toward the other to compensate for wear the nuts 13 of the bolt 8 are slightly loosened and the lock nut 12 is also slightly relieved whereupon the screw threaded sleeve 10 may be rotated by means of a wrench or spanner to screw the sleeve an additional distance into the main sleeve 9, thereby shortening the distance between the opposite ends of the sleeves 9 and 10. All of the spacer devices about the head 5 having been adjusted to the desired degree, the lock nuts 12 are then tightened to hold the sleeve 10 in adjusted position and the nuts 13 are tightened to draw the head 5 toward the main head 1 and into contact with the shortened spacer comprising the interengaged sleeves 9 and 10. In the event that it is desired to set the head 5 outward to accommodate new crushing discs of greater thickness, the nuts 12 and 13 are loosened and the screw threaded sleeve 10 is rotated to unscrew it from the sleeve 9, thereby extending the spacer member.

In lieu of the integral sleeve 9 comprising an integral steel or iron core and a manganese shell, as before described, the core and shell may be formed separate as shown in Fig. 4. In this construction the shell 9^c may be renewed from time to time while the core is continued in use.

In Fig. 3 there is shown a modification of the construction before described in which the sleeve 14 comprising a steel or iron core and a manganese exterior is provided with an integral stud 15 screw threaded for the engagement of a nut 16 by which it is secured to the head of the main head 1. The interior of the sleeve 14 is screw threaded to receive a screw threaded stud 17 having a head or shoulder 18 adapted to engage the inner face of the head 5 and a screw threaded extension 19 extending through the head 5 and carrying at the outer side thereof a nut 20. In this construction, by releasing the nut 20 and applying a wrench or spanner to the head 18 the stud may be rotated in its bearing in the head 5 to extend its screw threaded extremity a greater or less distance into the screw threaded bore of the sleeve 14, thereby drawing the parts 1 and 5 toward each other or forcing them apart

according to the direction of rotation of the stud 17. To accommodate the shoulder or head 18 in an extreme position of adjustment the sleeve 14 may be recessed as at 21.

In lieu of adjusting the studs 17 to vary the relation of the heads 1 and 5, the stud may remain locked in the head 5 by the nut 20 and the nut 16 upon the stud 17 may be loosened and a wrench or spanner applied to the sleeve 14 to rotate said sleeve and its integral stud 15 in its bearings within the main head 1 to cause the sleeve to be screwed a greater or less distance upon the stud 17.

It will be seen that by this construction the operator is not limited to any definite or arbitrary degrees of adjustment as in the case of the use of washers or shims and that the parts may be securely locked in any position of adjustment within the limits of the device. The operations of adjusting the device may be easily and quickly performed with considerable saving of labor and time. The device herein described may be incorporated in new machines at the time of manufacture or it may be applied to machines already installed and in use.

While this invention has been designed for and is here described in connection with rock or ore crushing apparatus, it is to be understood that it may be applied to other devices and is not limited to such association.

There is indicated at 22 in Figs. 1 and 2 a brace or stay ring which connects each spacer member with the adjacent spacer members. This stay member is not essential to the successful operation of the spacer device and may therefore be omitted. However, to permit the use of this stay or bracing member, if desired, the sleeve 9 is offset or shouldered as at 24 and the stay member is provided with a series of holes, one for each of the sleeves 9, within which the projecting end of the sleeve engages. The lock nut 12 bears upon the retaining or staying member 23 serving to connect the several spacer members rigidly one with the other. In the event that the stay or bracing member is omitted, the shoulder or offset 24 is likewise omitted from the sleeve 9.

From the above description it will be apparent that there is thus provided a device of the character described possessing the particular features of advantage before enumerated as desirable but which obviously is susceptible of modification in its form, proportion, detail construction, or arrangement of parts without departing from the principle involved or sacrificing any of its advantages.

While in order to comply with the statute the invention has been described in language more or less specific as to certain structural features, it is to be understood that the means and construction herein described comprise but one mode of putting the inven-

tion into effect and the invention is therefore claimed broadly in any of its possible forms of modifications within the scope of the appended claims.

5 Having thus described my invention, I claim:

1. A crusher of that type involving two relatively movable heads arranged in spaced relation, one of which is provided with a
- 10 peripheral shoulder, characterized by an internally screw threaded sleeve abutting upon the inner or adjacent face of one of said heads and extending entirely across the intervening space between said heads and
- 15 overhanging the peripheral shoulder of the other head, an externally screw threaded member abutting upon the inner or adjacent face of the shouldered head and adjustably engaging within the screw threaded
- 20 bore of said sleeve to limit the approach of said heads one toward the other, and limiting means preventing the separation of said heads.
2. A crusher of that type involving two relatively movable heads one of which is provided with a peripheral shoulder, said heads being interconnected one with the other by bolts, characterized by two interengaged screw threaded sleeves mounted upon one of
- 25 said bolts between said heads and forming an adjustable spacer for limiting the approach of said heads one toward the other, one of said sleeves being abutted upon one of
- 30 said heads and overhanging the peripheral shoulder of the other head.
- 35
3. A crusher of that type involving two relatively movable heads having a bolt interconnecting the heads one with the other characterized by an externally threaded sleeve loosely journaled upon the bolt and bearing at one end upon one of said heads, and an internally screw threaded sleeve engaging at one end the other of said heads and within the screw threaded interior of which the first mentioned sleeve is adjustably engaged, said sleeves being adjustable in relation one with the other to form an adjustable spacer to limit the approach of said heads, said last mentioned sleeve being of greater length than the intervening space between the adjacent faces of said heads.
4. A crusher of the type involving two relatively adjustable heads having adjustable spacer means intermediate the heads characterized by an internally screw threaded sleeve engaging one of the heads, and overhanging the periphery of the other head and an externally screw threaded member engaging the other of said heads at one end and interengaged with said sleeve whereby the relative adjustment of said sleeve and member will vary the limit of approach of said heads one toward the other.

In testimony whereof, I have hereunto set my hand this 19th day of June, A. D. 1916.

HARVEY S. ANDERSON.
